UNITED STATES PATENT OFFICE.

HOWARD L. KENNEDY, OF VAN WERT, OHIO, ASSIGNOR TO KENNEDY MANUFACTURING COMPANY, OF VAN WERT, OHIO, A CORPORATION OF OHIO.

CANTILEVER KIT.

Application filed March 10, 1927. Serial No. 174,157.

This invention relates to sheet metal carrying cases, and more particularly to such cases containing trays which may be moved into outwardly extending position.

5 An object of my invention is to provide a weather-proof sheet metal kit or case having a pair of covers and containing one or more trays movable into outwardly extended position by the opening of said covers.

10 Another object of the invention is to provide a case having advantageous structural features and characteristics.

A further object of the invention is to provide a sheet metal case containing a plurality 15 of trays with relatively high end walls, said end walls being so shaped to provide full access to said trays when said trays are in extended position.

Another object of the invention is to provide 20 an improved case having a pair of covers and containing a plurality of trays, certain of which are moved into outwardly extended position upon the opening of each of said covers.

25 Another object of my invention is to provide a sheet metal case having two series of superposed trays disposed side by side, said trays extending substantially the entire width of the case, storage space being provided within said case beneath said trays.

A further object of the invention is to provide in a sheet metal carrying case, advantageous means for supporting the trays within said case well above the bottom thereof.

35 Another object of my invention is to provide a sheet metal kit containing trays and having a pair of covers, said trays being so arranged that said covers will be supported when in closed position by the end walls of 40 said case.

45 Another object of this invention is to provide a sheet metal case having a pair of covers and a plurality of trays, certain of which are moved into outwardly extended position

upon the opening of each of said covers, wherein said covers when in open position are supported by said extended trays and in relatively closely adjacent position thereto.

50 Another object of my invention is to provide a neat and compact sheet metal carrying case which may be used for a wide variety of purposes, including, for example, the carrying of fishing tackle.

Other objects of the invention will be apparent to those skilled in the art from the description of it hereinafter given. 55

In the drawings:

Figure 1 is a perspective view of an improved sheet metal carrying case according 60 to my invention;

Fig. 2 is a front elevation partly in section of the case;

Fig. 3 is an end elevation of the case, one of the covers being shown in partly open position and the trays secured thereto being 65 shown in partly outwardly extended position;

Fig. 4 is a vertical section taken on line 4-4 of Fig. 2;

Fig. 5 is a fragmentary vertical section on 70 line 5-5 of Fig. 4, showing the connection of a link to a tray;

Fig. 6 is an end elevation of the case showing both covers in open position and all trays in outwardly extended position; 75

Fig. 7 is a fragmentary vertical section on line 7-7 of Fig. 4 showing the connection of certain links to a tray.

My invention contemplates a neat and compact sheet metal carrying case having a pair 80 of covers. The case is arranged to contain trays, certain of which are moved into outwardly extending position upon the opening of each of said covers. The trays may preferably be disposed in two series of superposed 85 trays within the case, the total width of the trays being substantially the same as that of the case in order to provide trays of maximum carrying capacity. The case is so arranged that when the covers are open, any 90 and all trays are entirely accessible to dispose articles in or remove articles from said trays. The trays, moreover, are arranged to be disposed well above the bottom of the case when the case is closed whereby to provide storage 95 space beneath said trays.

My improved case is shown as comprising the box 1 and covers 2 and 3. Within the case are shown the trays 4 and 5, and 6 and 7 movable with the covers 2 and 3 respectively. 100 When the case is in closed position the trays 5 and 7 are shown as superposed on the trays 4 and 6 respectively to form the laterally disposed series 8 and 9. Each series may comprise one or more trays and for certain purposes one of the series may be omitted. It 105

will be noted that the combined width of the two series of trays is substantially the same width as the box 1.

The box 1 is shown as comprising the bottom 10, side walls 11 and end walls 12. The side walls 11 and bottom 10 may, as shown in the drawings, comprise a continuous sheet of metal joined by suitable seams 13 and 14 (Fig. 1) to the end walls 12. The side walls 11 are shown as inwardly offset at 15 adjacent their upper edges, and the upper edges of the side walls 11 are shown as turned over at 16 to provide smoothness and rigidity.

The end walls 12 extend preferably to the top of the case, the portions of said end walls above the upper edges of the said side walls being preferably peaked or substantially triangular in shape for purposes to be herein-after more fully described. The peaked portions 17 of the end walls 12 may be inwardly flanged as indicated at 18 in Figs. 2 and 4 to provide rigidity and strength to said end walls as well as provide a smooth outer edge thereto. It may frequently be desired to provide a strengthening member of rib 19 inwardly of and adjacent said flanged portions 18, which said ribs 19 and flanges 18 may be secured together as by welding.

Spaced from the bottom 10 and secured to each of the end walls 12 are the brackets 20 which may be of angular cross section and which preferably contact with the respective end walls throughout their length. The brackets 20 may be secured to the end walls 12 by suitable means such as the rivets 21. The brackets 20 are shown as having horizontal upper surfaces 22 upon which the lower-most trays 4 and 6 may be disposed when the case is closed. The brackets 20 are also arranged to cooperate with links to be later described. The brackets 20 moreover have the substantially vertical portions 23 spaced from the end walls to which links may be secured.

The trays 4, 5, 6 and 7 are each shown as being of substantially rectangular shape, the trays being preferably of the same size. The trays are shown as symmetrically disposed with respect to the longitudinal center line of the box and are each shown as being of substantially the same length as the box 1 and as of approximately one-half the width thereof. The dimensions of said trays may, of course, be varied to suit particular circumstances. The trays may be divided into compartments of particular size and shape by suitable partitions (not shown) as is well known in the art.

The ends of the trays 4, 5, 6 and 7 may be reinforced by members 24 to provide a more rigid connection of said trays to the links to be later described. The members 24 may be secured to the trays 4, 5, 6 and 7 by any suitable means, such as by the hollow rivets 25.

In order that the trays may be moved into outwardly extending position and in order

that said trays may be moved by the covers 2 and 3, suitable linkage is provided. Thus, links 26 are secured to the brackets 20 and trays 4 and 6. Links 27 are secured to brackets 20 and trays 4 and 5, and 6 and 7 and links 28 are secured to trays 4 and 5, and 6 and 7. The links 26 and 27 may be advantageously secured to the substantially vertical portions 23 of the brackets 20 spaced from the end walls 12. The links 26, 27 and 28 are arranged to remain always in parallel relation to each other. Connections of the links to the brackets 20 and to the trays may be advantageously made by the hollow rivets 25. In order to prevent binding and to obtain smooth operation of the links, bushings 29 (Figs. 5 and 7) may be disposed intermediate the rivets 25 and the links.

In order that the trays may be operated by movement of the covers, links 30 are shown as secured to the tray 4 and cover 2, the tray 6 and cover 3, respectively. The links 30 are shown as secured to the trays 4 and 6 at the connections of the links 28 to said trays. The outer ends of the links 30 are shown as offset and as secured by the rivets 31 to the flanges 32 and 33 of the covers 2 and 3 respectively.

The cover 2 is secured to the inwardly offset portion of the side wall 11 by a suitable pintle 34. Referring particularly to Fig. 4, the cover 2 extends from the pintle 34 upwardly of and in substantially flush relation to the side wall 11. From a point slightly above the top of the tray 5 of the adjacent series 8, the cover extends toward the top of the end walls 12. The upper portion of the cover 2 is offset as at 35 and overturned at its upper edge at 36 for strength and rigidity and rests, when in closed position, upon the end walls 12. The cover 3 is hinged to the inwardly offset portion 15 of the side wall 11 by the pintle 37 and is disposed in substantially flush relation to the side wall 11. The cover 3 extends upwardly from the pintle 37 adjacent the trays 6 and 7. From a point slightly above the tray 7, the cover extends in an inclined manner toward the top of the end walls 12 over said end walls, and over the inwardly offset portion 35 of the cover 2, the outer edge of the cover 2 being overturned as at 38 for strengthening purposes. By reason of the inwardly offset portion 35 the covers 2 and 3 may meet in substantially flush relation. As mentioned above, when the covers are closed the cover 2 rests directly upon and is supported by the peaked portions 17 of the end walls 12. The covers 2 and 3 might, of course, be arranged to provide a substantially horizontal top but in general the inclined covers provide a case of more pleasing appearance.

The covers 2 and 3 are provided with the flanges 32 and 33 which overlie the end walls 12 thereby to protect the contents of the case from rain or snow or other conditions which

may injuriously affect the contents of the case. The overlying portions 32 and 33 are preferably shaped to provide a pleasing appearance as indicated in Fig. 1.

5 The covers 2 and 3 may be provided with suitable securing means 39 and 40 and the cover 3 may be provided with a suitable handle 41.

When the cover 2 is moved to open position, 10 the trays 4 and 5 are moved outwardly, as shown in Fig. 3, to outwardly extending position as shown in Fig. 6. Likewise, when the cover 3 is moved to open position, the trays 6 and 7 are moved to outwardly extending position as is also shown in Fig. 6. It will be noted that the height of the side walls 11 is such that the trays 4 and 6 may be readily moved thereover when the said trays are moved into outwardly extending position. 15 When in outwardly extending position, the trays 4 and 6 rest upon the brackets 20 and, if desired, the side walls 11 may be of such height that the trays 4 and 6 may rest thereon when in extended position. The covers 2 and 20 3, when in open position, are supported by links 30 from the trays, said links 30 being preferably of such length that the covers 2 and 3 may be maintained in relatively closely adjacent position to said trays.

30 Referring again to Fig. 6, it will be noted that the upper portion of the end walls 12 are so shaped that full access may be had to each of the trays 4 and 6 when the case is opened. In some cases, however, it may be desirable to 35 have the upper portions of the end walls 12 of rectangular shape rather than of the peaked shape shown in the drawings.

Referring particularly to Fig. 4, it will be noted that when the case is closed there 40 is relatively little waste space above the trays 5 and 7 and yet the case is of very pleasing appearance. It will moreover be noted that by means of my improved construction a storage space of any desired size may be provided 45 beneath the trays. In such cases the space beneath the trays may also be subdivided into suitable compartments by suitable well known partition members (not shown).

It will thus be seen by my construction 50 wherein the end walls extend substantially to the top of the case, that moisture such as rain cannot readily enter the case to damage the contents thereof.

It will further be noted that by arranging 55 suitable overlying cover portions cooperating with the relatively high side walls, that I have provided a kit which is of substantially weather-proof construction.

It will also be noted that I have provided 60 an improved construction of neat and compact character whereby trays may be readily disposed within the case well above the bottom thereof and movable into outwardly extended position by movement of the covers.

65 It will furthermore be seen that I have

provided an improved case construction wherein a plurality of series of superposed trays may be disposed, said trays being movable into outwardly extended position by a minimum movement of a pair of covers. 70

It will also be seen that I have provided a case containing a plurality of superposed trays, said trays being so arranged that when the case is in closed position the lowermost of said trays will rest in a position not lower 75 than the upper edge of the side walls.

It will moreover be noted that the inwardly offset portions of the side walls and covers also add rigidity to said respective members as well as provide flush meeting edges 80 of the covers with each other and with the respective side walls.

Furthermore, it is to be understood that the particular forms of apparatus shown and described, and the particular procedure set 85 forth, are presented for purposes of explanation and illustration and that various modifications of said apparatus and procedure can be made without departing from my invention as defined in the appended claims. 90

What I claim is:

1. In a sheet metal carrying case, in combination, a substantially rectangular box having end walls and side walls, said end walls extending substantially to the top of said case 95 and above the upper edges of said side walls, means carried by said box to support a tray above the bottom of said box, a tray supported on said supporting means, covers hinged to said side walls and cooperating to completely enclose said case, linkage connecting said box and tray, and linkage connecting said tray and one of said covers, whereby said tray may be moved into outwardly extending position upon the opening 100 of said cover, and vice versa, said tray supporting means being arranged to support said tray when said one cover is in either closed or open position.

2. In a sheet metal carrying case, in combination, a substantially rectangular box having end walls and side walls, said end walls extending substantially to the top of said case and above the upper edges of said side walls, brackets carried by said end walls arranged to support a tray in spaced relation to the bottom of said box, a tray supported on said brackets, a cover hinged to one of said side walls extending upwardly and toward the opposed side wall and resting, when in closed position, upon said end walls, a second cover hinged to the other of said side walls, extending upwardly and overlying said first cover, portions carried by said covers to overlie said end walls, linkage connecting said 115 box and tray, linkage connecting said tray and one of said covers, whereby said tray may be moved into outwardly extending position upon the opening of said cover, and vice versa, said end walls being so shaped 120

125

130

that said tray is fully accessible when in outwardly extending position.

3. In a sheet metal carrying case, in combination, a substantially rectangular box having relatively low side walls and end walls extending above the upper edges of said side walls substantially to the top of said case brackets secured to said end walls, each said bracket contacting throughout substantially its entire length with one of said end walls, said brackets having portions spaced from said end walls to which links may be secured and having tray supporting surfaces not lower than the upper edges of said side walls, a plurality of laterally disposed series of superposed trays supported on said tray supporting surfaces of said brackets, links secured to said link securing bracket portions and to said trays, covers hinged to said side walls and to cooperatively enclose said case and links connecting each said cover to certain of said trays, whereby said trays may be moved into outwardly extending position upon the opening of said covers, and vice versa.

4. In a rigid sheet metal carrying case, in combination, a substantially rectangular box having relatively low side walls and end walls extending above the upper edges of said side walls substantially to the top of said case, the portions of said end walls above said side walls being peaked, a metal reinforcing member bent into peaked shape and disposed interiorly of each said end wall adjacent the edge of each said peaked portion, the edge of the peaked portion of each said end wall being bent inwardly over each said reinforcing member to form an inwardly extending flange, brackets secured to said end walls, said brackets contacting with said end walls throughout substantially their entire lengths and having tray supporting surfaces not lower than the upper edges of said side walls, said reinforcing members and brackets imparting rigidly to said end walls, covers hinged to said side walls and cooperating to enclose said case, a tray supported on said bracket and connected by links to said brackets and to one of said covers whereby said tray may be moved into outwardly extending position upon the opening of said cover and vice versa.

5. In a sheet metal carrying case, in combination, a substantially rectangular box having relatively low side walls and end walls extending above the upper edges of said side walls substantially to the top of said case, the portions of said end walls above said side walls being peaked, brackets secured to said end walls, said brackets contacting with said end walls throughout substantially their entire length and having tray supporting surfaces not lower than the upper edges of said side walls, a plurality of laterally disposed series of superposed trays sup-

ported on said tray supporting surfaces of said brackets, the lowermost of each series of trays having a width equal to approximately one-half the width of said box, links secured to said brackets and to the ends of said trays, a first cover hinged to one of said side walls extending upwardly substantially to the top of the adjacent series of trays and thence toward the opposite side wall and resting upon said end walls, a second cover hinged to the other side wall extending upwardly substantially to the top of the adjacent series of trays and thence toward said first side wall to overlie said first cover, and links secured to each series of trays and to the adjacent cover whereby a series of trays may be moved into outwardly extending position upon the opening of each cover and vice versa, in which outwardly extending position the lowermost of said series of trays will be supported on said tray supporting surfaces of said brackets.

6. In a rigid sheet metal carrying case, in combination, a substantially rectangular box having relatively low side walls and end walls extending above the upper edges of said side walls substantially to the top of said case, the portions of said end walls above said side walls being peaked, said side walls having inwardly offset portions adjacent their upper edges, a metal reinforcing member bent into peaked shape and disposed interiorly of each said end wall adjacent the edge of each said peaked portion, the edge of the peaked portion of each said end wall being bent inwardly over each said reinforcing member to form an inwardly extending flange, means carried by said box to support trays well above the bottom of said box, a tray supported on said supporting means, a first cover hinged to the inwardly offset portion of one of said side walls extending upwardly and thence toward the opposite side wall, said cover having an inwardly offset portion including its upper edge resting upon said end walls, a second cover hinged to the inwardly offset portion of the other side wall extending upwardly over the top of said end walls and overlying the inwardly offset portion of said first cover, whereby to provide flush meeting edges of said covers with the respective side walls and with each other, and linkage connecting said tray and one of said covers whereby said tray may be moved into outwardly extending position upon the opening of said cover and vice versa.

7. In a sheet metal carrying case, in combination, a substantially rectangular box having end walls and side walls, said end walls extending substantially to the top of said case and above the upper edges of said side walls, means carried by said box to support a tray above the bottom of said box, a tray supported on said supporting means, covers hinged to said side walls and cooperat-

ing to completely enclose said case, links disposed between said box and tray, rivets securing said links to said box and tray respectively, bushings disposed intermediate said 5 links and rivets whereby to provide smoothly operating link mechanism, and linkage connecting said tray and one of said covers whereby said tray may be moved into outwardly extending position upon the opening 10 of the cover and vice versa.

8. In a sheet metal carrying case, in combination, a substantially rectangular box having end walls and side walls, said end walls being peak-shaped and extending substan-

tially to the top of said case and above the 15 upper edges of said side walls, means carried by said box to support trays above the bottom of said box, covers hinged to said side walls, a pair of trays supported on said supporting means, linkage connecting said box 20 and trays and connecting each of said trays with one of said covers, said covers overlapping the peak-shaped end walls, whereby a rigid construction is provided, and the trays and link mechanism are protected from end 25 shocks.

In testimony whereof I affix my signature.
HOWARD L. KENNEDY.
